UNITED STATES PATENT OFFICE

165,272

COMBINATION HUMIDIFIER AND ARTIFICIAL FLOWER HOLDER

John Dioguardi, Brooklyn, N. Y.

Application December 23, 1950, Serial No. 13,615

Term of patent 14 years

(Cl. D35—3)

To all whom it may concern:

Be it known that I, John Dioguardi, a citizen of the United States, residing at Brooklyn, in the county of Kings and State of New York, have invented a new, original, and ornamental Design for a Combination Humidifier and Artificial Flower Holder, of which the following is a specification, reference being had to the accompanying drawing, forming part thereof.

Fig. 1 is a perspective view showing the top, front and one side of a combination humidifier and artificial flower holder, embodying my new design;

Fig. 2 is a perspective view showing the top, rear and other side thereof; and

Fig. 3 is a bottom plan view thereof.

I claim:

The ornamental design for a combination humidifier and artificial flower holder, as shown.

JOHN DIOGUARDI.
